MOTOR CONTROL FOR CENTRIFUGES

Clarence F. Dinley, Detroit, Mich., assignor to
Detrex Corporation, Detroit, Mich., a corpora-
tion of Michigan

Application March 24, 1948, Serial No. 16,868

5 Claims. (Cl. 318—163)

1

This invention is concerned with the driving of machinery such as rotary extractors or driers, cement mixers, steel mills, agitators, turbines, printing presses, etc., by means of electric motors. The operation of such machines at high speeds is usually attended by excessive vibration due, for the most part, to uneven or unbalanced distribution of the materials undergoing treatment in them. The vibration so induced is not only objectionable from the standpoint of the noise incidentally created, but also by reason of the rapid wear it occasions in the machines so driven.

My invention has for its chief aim to overcome the above mentioned drawbacks. This desideratum is realized in practice as hereinafter more fully set forth, through provision of automatic means whereby the voltage impressed on the driving motors is changed step by step and the different voltages maintained for different intervals for development of variant prescribed torque values requisite to the acceleration of the centrifuges at such rates that the load is afforded ample opportunity to adjust itself before the desired maximum speed is reached.

Other objects and attendant advantages will appear from the following detailed description of the attached drawings, wherein: Fig. 1 is a diagrammatic view showing by way of example, a centrifuge with driving mechanism therefor embodying my invention; and

Fig. 2 is a graph showing a prescribed torque curve in accordance with which the potential impressed upon the motor is changed at varying intervals to start the centrifuge and control its acceleration in accordance with my improved method.

Referring in greater detail, first more especially to Fig. 1 of these illustrations, the numeral 5 represents a centrifuge which may be the horizontal axis cylindric drum of an extractor such as is used in dry cleaning operations to expel entrained moisture from a mass of textile materials or articles 6 placed within it subsequent to treatment with solvent fluid. At M is indicated an electric motor which will be understood to be of a variable speed alternating current type, and which is relied upon to drive the centrifuge 5 through a mechanical connection in the form of a chain or belt 8.

The means which I have devised for control- 50
ling the driving motor M of an organization such as above exemplified, includes an auto trans-
former 9 which, by means of leads 9a and 9b, is
connected across the conductors 10 and 11 of a
220 volt power line, and which is shown as hav-

ing 220 volt, 130 volt and 160 volt taps, one terminal 12 of the motor M being connected by a conductor 13 directly to the side 10 of the power line. The control means further includes a rotary timer T whereof the shaft 16 is arranged to be driven, through speed reduction gearing 17, by a small synchronous motor designated M'. Secured to the shaft of the timer T are pairs of rotary cams 19, 20; 21, 22; 23, 24; 25, 26 and 27, 28 for actuating corresponding pairs of downwardly spring biased switch contacts 19a, 20a; 21a, 22a; 23a, 24a; 25a, 26a and 27a, 28a.

Through conductors 19b, 21b, 23b, and 25b, the switch contacts 19a, 21a, 23a, and 25a are all connected to a lead 30 extending from the conductor 11 of the power line; and through other leads 20b, 22b, 24b, and 26b the switch contacts 20a, 22a, 24a, and 26a are connected to corresponding terminals of the magnet coils 31, 36, 41 and 46 of relays R, R', R2 and R3 respectively, the other terminals of said coils being all connected to a conductor 39 which extends to the lead 9b, of the transformer 9. Contact 32 of relay R is connected, through a lead 52, to the lead 9a of transformer 9; and contact 33, through a lead 53 to the contact 39 of relay R'. Contact 37 of relay R' is connected, through a lead 57, to the 130 volt tap of transformer 9; contact 38, through a lead 55, to contact 44 of relay R2; and contact 40, through leads 56 and 57, to one terminal 58 of motor M. Contact 42 of relay R2 is connected, through a lead 59, to the 160 volt tap of transformer 9; contact 43, through a lead 60, to contact 49 of relay R3; and contact 45, through a lead 61, to the conductor 57. Contact 47 of relay R3 is connected, through a lead 63, to the 220 volt tap of transformer 9; while the contacts 48 and 59 are connected together and to the conductor 57.

Switch contact 27a of the timer T is connected, through a lead 27b, to the terminal 63 of the synchronous motor M', the other terminal 64 of said motor being connected, through a lead 65, to the line conductor 11. The switch contact 28a is connected, through a lead 28b, to the line conductor 10; and bridging the leads 27b, 28b is a conductor 66 in which is interposed a push button switch 67 for starting the timer motor M'.

Operation

The several cams of the timer T are adjusted circumferentially and set on the shaft 16 to determine an operative cycle of the motor M as follows:

Let it be assumed that the time required for

extraction is four minutes and that the timer is designed to turn through a complete rotation for each extraction cycle. Upon pressing the push button 67, the synchronous motor M' is set in motion to rotate the timer shaft 16 in the direction indicated by the arrow on one of the cams. In a second or so after starting, the high point of the cam 27 is advanced from beneath the switch contact 27a which is thereby suddenly freed to drop and close upon the contact 28a so that the motor M' keeps running after release of the push button 67. Immediately thereupon, the high point of cam 19 will pass beyond the switch contact 19a allowing the latter to drop and close upon the contact 20a, with consequent current flow through the magnet coil 31 of relay R by way of conductors 20b, 39 and 9b. By actuation of the relay R, the armature thereof closes the contacts 32 and 33 so that current at 220 volts will pass through the motor M, the course of the current, starting with the line conductor 11, being by way of the conductor 9a, contacts 32 and 33 of relay R, conductor 53, armature and contacts 39, 40 of relay R', conductors 56, 57 motor M and conductor 13 to the power line conductor 10. The setting of the cam 21 is such that, after the expiration of six seconds from the time of closing the contacts 19a, 20a, its high point will underpass the switch contact 21a whereupon the latter, in dropping, will close upon the contact 22a.

During this interval of six seconds at the 220 volt potential, sufficient torque is developed in the motor M to overcome the inertia of the centrifuge 5 and bring it to a rotative speed of approximately 725 R. P. M. at the point a on the torque curve A of the graph in Fig. 2. Upon closing of the switch contacts 21a, 22a, current will flow from the power line conductor 11, by way of conductors 30, 21b, 22b, coil 36 of relay R' and conductors 39 and 9b, to power line conductor 10. By consequent actuation of relay R', the armature of the latter breaks with the contacts 39, 40 and makes with the contacts 31, 33 whereupon current at 130 volts will be impressed upon the motor M, the current flow being from the power line conductor 11 by way of conductor 9a, the large portion of transformer 9, conductor 57, armature and contacts 31, 33 of relay R', conductor 55, armature and contacts 44, 45 of relay R2, conductors 61 and 51 through the motor M, and thence through the conductor 13 to the line conductor 10. The setting of the timer cam 23 is such that at the expiration of twenty-nine seconds from the time of closing of the contacts 21a, 22a, its high point will clear the contact 23, which in dropping, will close upon the contact 24a. During the aforementioned interval of twenty-nine seconds with supply of current at 130 volts to the motor M, the requisite torque will be developed to accelerate the centrifuge 5 at a relatively low rate from 725 R. P. M. from the point a on the torque curve A of the graph in Fig. 2 to 1080 R. P. M. at the point a¹.

By closing of the switch contacts 23a, 24a, current will flow from the power line conductor 11 by way of the conductors 30, 23b, 24b through coil 41 of relay R2, and from thence through the conductors 39 and 9a to the power line conductor 10. By ensuing actuation of relay R2 its armature will break with contacts 44, 45 and make with contacts 42, 43. Current at 160 volts will thereupon flow from power line conductor 11, by way of the lead 9a, through a large part of the transformer 9, then by way of conductor 59, armature and contacts 42, 43 of relay R2, conductor 60, armature and contacts 49, 50 of relay

R3, and conductor 51 to motor M, and then from the latter to the power line conductor 10. At this higher voltage, sufficient torque will be developed in the motor to further accelerate the centrifuge, 5 still at a relatively slow rate as before, from 1080 R. P. M. at the point a¹ to 1500 R. P. M. at the point a² on the torque curve A of the graph. This voltage will be maintained for fifty-one seconds when the high point of the timer cam 25 will underpass and release switch contact 25 to close upon contact 25b. When this occurs, current will flow from power line conductor 11 by way of conductors 30, 25b, 25b to coil 46 of relay R3, and from the latter, through conductors 28 and 9b, 10 to the power line conductor 10. Upon resultant actuation of the relay R3, a new circuit will be established through motor M with current flow at 220 volts, by way of conductor 9a, transformer 9, conductor 63, armature and contacts 47, 48 of relay R3, and conductors 51, 13. The torque thereby developed will accelerate the centrifuge 5 within about ten seconds from a speed of 1500 R. P. M. at the point a² on the torque curve A to the desired maximum speed of 1800 R. P. M. at the point a³ at which it will thereafter be maintained until the completion of the extraction cycle. By controlling the acceleration in this way between the points a and a² through step-wise increase in the voltage impressed upon 15 motor M, the material being extracted is afforded the opportunity to adjust itself within the centrifuge before the latter attains the desired maximum speed, so that no vibration and noise will attend its operation when it is finally driven at 20 full speed.

The amperage curve B on the graph shows how the current supplied to the motor M from the time of starting at 220 volts and through the changes in the voltage first to 130, then to 160 25 and finally back to 220 during the successive acceleration periods of six, twenty-nine, fifty-one, and ten seconds. During the remainder of the timer rotation, which takes about two minutes and forty seconds, the cams 20, 22, 24, and 26 gradually raise the contacts 20a, 22a, 24a and 26a, keeping them closed with the contacts 19a, 21a, 23a and 25a respectively. At the completion of the rotation, the high points of the cams 20, 22, 24, and 26 underpass the switch contacts 20a, 22a, 24a and 26a and simultaneously release them 30 to fall away from the contacts 19a, 21a, 23a, and 25a, whereby all the circuits to motor M are broken as in Fig. 1. Also at the same time, the high point of cam 28 will underpass the contact 28a which, in dropping, will interrupt the circuit 35 through the synchronous motor M', likewise as shown in Fig. 1 with consequent completion of the cycle.

It is to be understood that the values herein used to exemplify my invention are subject to wide variation in actual practice depending upon the capacities and sizes of the driven machines, the materials which are to be extracted, and the ratings of the driving motors. I do not, moreover, consider myself restricted to the employment of the specific circuit control devices which have been shown and described by way of illustration, since in practice, these may be replaced by equivalents capable of performing like functions as will be readily understood by those skilled in the art of electric motor control.

Having thus described my invention, I claim:

1. The method of accelerating a single phase A. C. electric motor-driven centrifuge or the like with an initially unbalanced load, which comprises impressing upon the motor line voltage

for a short time interval sufficient for development of requisite torque to start rotation of the centrifuge, then reducing the voltage to a point for development of requisite torque for acceleration of the centrifuge at a different rate during a predetermined time interval, and thereafter increasing the impressed voltage step by step up to line voltage for development of different degrees of torque requisite for acceleration of the centrifuge at correspondingly different rates during different predetermined time periods whereby the initially unbalanced load is afforded the opportunity to adjust itself within the centrifuge before the latter attains the desired maximum speed.

2. In mechanism for accelerating an electric motor-driven centrifugal with an initially unbalanced load from rest to full speed, a transformer connected across a power line and having a plurality of different voltage taps; normally-open switches respectively interposed in conductors connected to individual taps of the transformer in a wiring system containing the motor; and cycle timing means comprising a shaft with rotary cams thereon arranged to actuate the several switches in succession, an electric motor with reduction gearing for driving the shaft, a manual starting switch in circuit with the motor, a normally open auxiliary switch connected in parallel with the manual switch, and an additional cam on the timer shaft for closing the auxiliary switch upon starting of the latter motor and for opening said auxiliary switch at the completion of a single rotation of the cam shaft.

3. In mechanism for accelerating an electric motor-driven centrifuge with an initially unbalanced load from rest to full speed, a transformer connected across a power line and having a plurality of different voltage taps; normally-open relays interposed respectively in conductors connected to the individual taps of the transformer and one in a conductor independent of the transformer comprised in a circuit containing the motor; and cycle timing means including normally-open switches interposed with the actuating coils of the respective relays in conductors of another circuit, a shaft with rotary cams thereon arranged to selectively actuate the several switches, an electric motor with reduction gearing for driving the shaft, a manual switch in circuit with the motor, a normally-open auxiliary switch connected in parallel with the manual switch, and an additional cam on the shaft for closing the auxiliary switch upon starting of the latter motor and for opening said auxiliary switch at the completion of a single rotation of the cam shaft.

4. In mechanism for accelerating an electric motor driven centrifuge with an initially unbalanced load from rest to full speed, a transformer connected across a power line and having a plurality of different voltage taps; normally-open relays interposed in conductors connected to the respective taps of the transformer in a wiring circuit containing the motor; and cycle timing means including separate normally-open switches interposed with the coils of the relays in conductors in parallel in another circuit of the wiring system, a shaft with rotary cams thereon arranged to selectively actuate the switches to cause closing in turn of the corresponding relays for impression upon the motor for different time intervals, of different voltages through the respective taps of the transformer, and means for turning the shaft through a complete rotation for each operating cycle of the centrifuge.
5. In mechanism for accelerating an electric motor driven centrifuge with an initially unbalanced load from rest to full speed, a transformer connected across a power line and having a plurality of different voltage taps; normally-open relays interposed in conductors connected to the respective taps of the transformer and one in a conductor independent of the transformer comprised in a circuit containing the motor; and cycle timing means including normally-open switches interposed with the coils of the respective relays in conductors of another circuit and cycle timing means comprising a shaft with rotary cams thereon for selectively closing the several switches to cause closing, in turn, of the corresponding relays for impression upon the motor for different time periods, of different voltages through the different taps of the transformer and of full line voltage by way of the aforesaid separate conductor, and means for turning the shaft through a complete rotation for each operating cycle of the centrifuge.

CLARENCE F. DINLEY.
